UNITED STATES PATENT OFFICE

118,127

DESIGN FOR A COMBINATION KITCHEN TOOL

James A. Murdock, Chicago, Ill.

Application October 27, 1939, Serial No. 87,894

Term of patent 14 years

To all whom it may concern:

Be it known that I, James A. Murdock, a citizen of the United States, residing at Chicago, in the county of Cook and State of Illinois, have invented a new, original, and ornamental Design for a Combination Kitchen Tool, of which the following is a specification, reference being had to the accompanying drawing, forming part thereof.

I claim:

The ornamental design for a combination kitchen tool, as shown.

JAMES A. MURDOCK.
